WILLIAM E. ANDRÉE, OF CHICAGO, ILLINOIS, ASSIGNOR TO THE AMERICAN LAUNDRY MACHINERY COMPANY, OF NORWOOD, OHIO, A CORPORATION OF OHIO.

LOCKING AND RELEASE TREADLE MECHANISM FOR GARMENT PRESSES.

1,403,826.

Specification of Letters Patent. Patented Jan. 17, 1922.

Application filed November 8, 1919. Serial No. 336,573.

To all whom it may concern:

Be it known that I, WILLIAM E. ANDRÉE, a citizen of the United States, residing at Chicago, in the county of Cook and State of Illinois, have invented certain new and useful Improvements in Locking and Release Treadle Mechanism for Garment Presses, of which the following is a specification.

This invention relates to garment presses of the type employing an upper pressing member or head cooperatively related to a bed or garment support, relative pressing movement between said members being produced by a foot treadle. More specifically 15 the invention relates to the locking and release treadle mechanism for such presses.

The object of the invention is to provide improved mechanism for locking and releasing the pressure treadle together with means 20 operable at will for rendering the locking and release mechanism ineffective to thereby secure free movement of the pressure treadle without any effect thereon by the locking or release mechanism, and other 25 mechanism for restoring the parts to effective position.

Further objects of the invention are in part obvious and in part will appear more in detail hereinafter.

30 In the drawings, which represent one suitable embodiment of the invention, Fig. 1 is a side elevation showing the press closed with the treadle mechanism locked; Fig. 2 is a detail sectional plan view on the line 2—2, Fig. 1; Fig. 3 is a detail sectional elevation of the free motion treadle mechanism, the section being taken substantially on the line 3—3, Fig. 6; Fig. 4 is a side elevation of the treadle mechanism with the 35 top of the press broken away, the pressure treadle being shown in release position; Fig. 5 is a front view thereof; Fig. 6 is a sectional elevation on the line 6—6, Fig. 5; and Fig. 7 is a side elevation of the treadle 40 mechanism, showing the free movement treadle in operative position.

Since the present invention relates entirely to the locking and release mechanism and its cooperative relation to the operating 50 member or pressure treadle of the press the particular form or arrangement of the press or of its operating mechanism is not material. For purposes of illustration, however, the press and its operating mechanism are 55 illustrated and described as of the form

shown, described and claimed in my copending application for garment press, filed of even date herewith, Serial No. 336,575. Briefly described so far as description is necessary for the present application, the 60 press comprises a frame 1 carrying a stationary bed or garment support 2 and on an upwardly extending post 3 on which frame is pivotally mounted a swinging lever carrying an upper pressing member or head 4. 65 The swinging lever comprises two members 5 and 6 pivoted together at 7, adjustable relatively to each other by the screw 8 and connected to suitable means for opening the press, such as tension springs 9. The press 70 closing mechanism comprises a pressure treadle 10 pivoted to the frame at 11 and provided with the foot plate 12, said treadle being connected by a link 13 to one arm 14 of a lever pivoted at 15 in the frame, the 75 other arm 16 of said lever serving as one member of a toggle which is pivotally connected at 17 to a toggle link 18 connected at its other end to the lower end of member 6. When the treadle is depressed the toggle 80 16, 18 is straightened and pressure is applied to a garment or any other work lying between the pressing members.

The locking and release treadle mechanism forming the subject matter of the present invention has for its purpose to lock the pressure treadle 12 in its depressed position, enable said treadle to be released when desired, together with a special operating member, such as a treadle, which can be depressed or otherwise operated to render the locking and release treadle mechanism ineffective. This mechanism will now be described.

On the front portion of the frame is 95 mounted a bracket or support 19 to which is pivoted at 20 a locking lever 21, the upper arm 22 of which is pressed outwardly by the compression spring 23, and the lower arm 24 of which is provided on one side 100 with a rib 25 having an inclined cam surface 26, a longitudinal surface 27 and a transverse bottom toe portion 28. The pressure treadle 10 on one side is provided with a pin 29 carrying an anti-friction member, 105 such as a roller 30. When the pressure treadle is depressed this roller engages the cam surface 26, pushes out the lower arm of the locking lever and passes along the straight surface 27 until said roller is be- 110

yond the toe 28, which thereupon springs in above the roller 30 so as to positively lock the pressure treadle in its depressed position, as shown in Fig. 1.

5 The locking lever 21 has pivoted to one side thereof, as at 31, a release treadle 32 provided with a foot plate 33, a rearwardly extending release lug 34, a stop 35 adapted in one position, shown in Fig. 6, to engage 10 an abutment 36 on the front of the lever 21 and in a second position, shown in Fig. 7, to engage a second abutment 37 on a forward extension 38 of lever 21, and is also provided with an upwardly extending arm 39 provided with a finger 40.

15 In release position of the press the release treadle 32 drops to its lowest position with its lug 34 beneath the toe of the locking lever. As the roller 30 on the pressure treadle moves to its locked position and passes the end of lever 21 it reaches a position directly behind the end of the lug 34, so that when the locking lever 21 moves rearwardly to locking position above the 20 roller the lug 34 prevents rearward motion of the lower end of the release treadle. Consequently said treadle swings about its pivot in the counter clockwise direction, Fig. 6, to the position shown in Fig. 1. In 25 this position with the lug 34 abutting the roller 30 the lower arm of the release treadle may be made to function as a toggle member with the lower arm of lever 21. Pressure on the foot plate of the release treadle therefore straightens said toggle and pulls out the lower arm of lever 21 until finally the 30 roller 30 is released from the toe 28 and moves upwardly along the surfaces 27 and 26 until the press is fully released. While 35 said roller moves along surface 26 the locking lever gradually moves in to its normal position, leaving the parts in the position shown in Fig. 4. This arrangement enables 40 heavy release pressure to be applied for unlocking and releasing the press. When the locking and release mechanism is employed the parts of the operating mechanism for the pressing head are so adjusted, such as by 45 adjusting the lengths of links 13 and 18, or by adjustment of the screw 8, that the toggle 16, 18 does not quite fully straighten when the press is locked. Consequently the 50 springs 9 immediately tend to open the press when the pressure treadle is released.

55 The free motion treadle mechanism comprises parts as follows:

On a stationary bracket or support 41 is pivoted the free motion treadle 42, which is normally held in its upper position by a 60 tension spring 43 extending from said lever to a fixed support, as at 44. This spring extends along one side of the lever and is above the pivot of the lever when the lever is in its upper position. The front end of 65 the spring moves down with the lever so

that when said lever is in its lowest position its tension is exerted below the lever pivot so that the spring always tends to hold the lever in its upper or lower position, as the case may be. Lever 42 is provided with a 70 short arm 45 which normally contacts an abutment 46 on the bracket 41 to limit upward lever motion. It also carries a free swinging wedge member 47, best shown in Figs. 4 and 7. 75

Let us assume that the press is in release position, as shown in Fig. 4. If the free motion treadle 42 is depressed, the wedge 47 is forced downwardly into position between a roller 48 carried by the pivot of the release treadle 32 and a fixed portion of the frame until the parts reach the position shown in Fig. 7. At the same time the free motion treadle engages the finger 40 of the release treadle and tilts said treadle outwardly until its lug 35 contacts the abutment 37. In this position of the parts the locking lever 21 is wholly removed from the path of movement of the roller 30 on the pressure treadle 10. Consequently said pressure treadle can be moved up and down without affecting or being affected by the locking or release mechanism. The free motion treadle is therefore useful whenever it is desirable to operate the press without locking the pressing treadle, a condition frequently met with in this art. When it is desired to cause the locking and release mechanism to resume its functions the release treadle 32 is depressed, and the tilting motion of said treadle raises the finger 40, 80 tilts the free motion treadle 42 upwardly and withdraws the wedge from its position between the roller 48 and frame, whereupon 85 the spring 43 restores the locking lever to its 90 original position, all parts thereupon functioning as before. 100

The free motion treadle can be operated with the press either open or closed. If the press is open operation of the free motion treadle merely moves the locking arm 21 out to its inoperating or ineffective position. If the press is closed and the pressure treadle is locked operation of the free motion treadle not only moves the arm 21 to its inoperative position but also releases the pressure treadle which immediately swings upwardly. 115

The invention is of course not limited to use with garment presses but may be applied to any machine where a machine part is operated by some movable operating member and it is desirable to lock and release the operating member or to permit it to operate with free motion. 120

125 What I claim is:

1. The combination with a movable pressing member and an operating member therefor, of yielding means located on a relatively stationary part operated by movement 130

- of said operating member for locking the same against movement, and means also located on a relatively stationary part for rendering said locking means ineffective.
5. 2. The combination with a movable pressing member and an operating member therefor, of means for locking said operating member against movement, a release member for said locking means, and means effective 10 upon both said locking means and release member and adapted when operated to move the same to ineffective position.
3. The combination with a movable pressing member and an operating member 15 therefor, of a yielding locking member for said operating member located on a relatively stationary part, and a movable release member carried by said locking member.
4. The combination with a movable 20 pressing member and an operating member therefor, of a swinging locking member for said operating member, and a release member pivoted to said locking member, and having a portion abutting a relatively fixed part, 25 whereby said locking and release members function as toggle mechanism for the release operation.
5. In a garment press, relatively movable 30 pressing members, operating means therefor, means for locking the press in closed position, and toggle means for releasing said locking means.
6. In a garment press, relatively movable 35 pressing members, operating means therefor, means for locking the press in closed position, releasing means for said locking means and a foot treadle for rendering said locking means ineffective.
7. In a garment press, relatively movable 40 pressing members, operating means therefor, means for locking the press in closed position, toggle release means for said locking means, and means for rendering said locking
- means ineffective, said last named means being adapted for operation by said toggle release means.
8. In a garment press, relatively movable 45 pressing members, a treadle for actuating the same, a movable member for locking said treadle, and a release treadle pivoted thereto.
9. In a garment press, relatively movable 50 pressing members, a treadle for actuating the same, a movable member for locking said treadle, a release treadle pivoted thereto, and a free motion treadle adapted when operated 55 to render said locking means ineffective.
10. In a garment press, relatively movable 60 pressing members, a treadle for actuating the same, a movable member for locking said treadle, a release treadle pivoted thereto, and a free motion treadle adapted when operated 65 to render said locking means ineffective, said free motion treadle being so arranged that when actuated it moves said release treadle to a new position for actuation to restore the parts to operative condition.
11. A garment press, comprising relatively 70 movable pressing members, a treadle adapted when actuated to produce pressure there between, a yieldable swinging locking member for said pressure treadle, and a free motion treadle cooperating with said locking lever and adapted when actuated to render the same ineffective.
12. A garment press, comprising relatively 75 movable pressing members, a treadle adapted when actuated to produce pressure there between, a yieldable swinging locking member for said pressure treadle, a free motion treadle cooperating with said locking lever 80 and adapted when actuated to render the same ineffective, and means for restoring said free motion treadle to initial position.

In testimony whereof I affix my signature.

WILLIAM E. ANDRÉE.
